UNITED STATES PATENT OFFICE.

GEORGE W. REDEKER, OF WHEELING, WEST VIRGINIA.

FLUSHING APPARATUS FOR WATER-PIPES.

1,016,521.

Specification of Letters Patent.

Patented Feb. 6, 1912.

Application filed December 8, 1910. Serial No. 596,344.

To all whom it may concern:

Be it known that I, GEORGE W. REDEKER, a citizen of the United States of America, and resident of Wheeling, county of Ohio, and 5 State of West Virginia, have invented certain new and useful Improvements in Flushing Apparatus for Water-Pipes, of which the following is a specification.

This invention relates to a device for flushing water service pipes.

The primary object of the invention is to provide an apparatus whereby sediment and obstructions may be readily and conveniently removed from house service water pipes 15 without the trouble and inconvenience of digging up streets and side-walks.

A further object is to provide an apparatus of the character mentioned whereby a violent shock may be given to the column of 20 water contained in the service pipes for dislodging foreign matter or obstructions, after which, when the shocking force is relieved, the obstructions and sediment are discharged under the pressure of the water.

25 A still further object is to provide means whereby material having a cutting or abrasive action may be forced through the pipes of a water service system for clearing the same of scale and closely adhering foreign 30 matter.

With these and other objects in view, the invention consists in the particular construction, arrangement and combination of parts which will hereinafter be fully described, reference being had to the accompanying drawings, forming a part of this specification, in which—

Figure 1 is a diagrammatic view of the invention applied to a water-service line, the 40 pressure-tank inclosing cylinder being shown in longitudinal section; and Fig. 2 is a section on the line 2—2, Fig. 1.

Referring to said drawing, in which like designating characters distinguish like parts 45 throughout the several views—1 indicates a tank which is preferably filled with carbonic acid gas at high pressure, but which may contain any other suitable compressed gas, air, gas-forming chemicals, or gaseous 50 or liquid material capable of discharging

therefrom at continued high pressure. Said tank is preferably inclosed within a closed cylinder or casing 2 for a purpose which will presently be explained.

A suitable valve 3 is provided at the discharge end of the tank, the same being operated in any appropriate manner, as by a key 4 directed through the adjacent end of the cylinder 2. Leading from said valve and extending outward through said cylinder is 55 a small discharge pipe 5 which is connected to a larger pipe 6 having a gate-valve 7 thereon, the last-mentioned pipe being connected to one end of a pipe 8 whose opposite end is adapted for having a flexible pipe or 60 hose 9 attached thereto. Said hose is adapted for having its opposite end attached to a house-service water pipe 10 at any suitable point, as at a faucet or other convenient point for admitting the applied pressure to 65 70 said service pipes.

A pressure gage 11 and a pop safety or relief valve 12 are provided on the pipe 8, the former for indicating the pressure admitted therethrough to the service pipes, and 75 the latter for permitting of the escape of pressure when it exceeds a predetermined point, preventing bursting of pipes.

In practice, when the hose connection has been made to the service pipes, the gate-valve 7 is opened so as to allow the water in said pipes to flow back to the valve 3 of the pressure tank 1. The said valve 3 is then opened quickly to suddenly release a heavy, or the full, pressure of the gas in the tank. 80 Owing to the fact that water is practically non-compressible, the impact of the gas with the column of water in the pipes, due to the sudden release of the gas, produces a violent shock and induces a sudden recoil in 85 the water column which extends throughout the entire length of said pipes. This violent movement of the water, resulting from the impact, loosens or detaches the scale, sediment and other foreign matter in the pipes. 90 The valves 3 and 7 are then simultaneously closed and a valve 14 in a drain pipe 15 connected to the pipe 8 is immediately opened. This permits the water in the service pipes 95 to rush out through drain-pipe 15 under 100

full pressure, carrying therewith the dislodged foreign matter; or, if desired, the hose may be disconnected from the faucet and said matter permitted to discharge from the latter.

In some cases it will be found that the pipes have become corroded, or that an obstruction exists in the pipes which effectually resists dislodgment under the violent shock due to the sudden release of the gas. In such cases, I interpose between the hose 9 and the service pipe 10 a connection which is herein designated generally by the numeral 16 and which consists of a pipe 17 having direct connection at its opposite ends with said hose 9 and pipe 10, and a by-pass pipe 18 connected at opposite ends to said pipe 17 adjacent to the ends of the latter. A pair of gate-valves 19 is provided on said pipe 17 between the connections of the by-pass pipe thereto, one of said gate-valves being located adjacent to each of said connections. The portion of said pipe 17 which is between said gate-valves is filled with a material which, when forced through the service pipes, will scrape and scour said pipes, cracked ice being preferably employed for this purpose, for the reason that portions thereof remaining in the pipes will readily melt and present no permanent obstruction. Either prior to the application of the pressure from the tank 1, or prior to closing off said pressure, as hereinbefore explained, according to the direction which it is desired the ice shall take, the gate-valves 19 are opened and the valves 20 adjacent to opposite ends of by-pass pipe 18 are closed. Pressure from the tank applied slowly, or the pressure of water returning through the pipes, as the case may be, forces the ice through the pipes, the irregular edges of the ice serving to effectually scrape and scour said pipes and to carry therebefore the dislodged foreign matter contained by the latter. When it is desired to direct the ice and dislodged material outward through the hose, the pipe 17 is filled with ice and the gate valves 19 closed. The valves 20 then being opened, the water from the main passes around on both sides of the pipe 17 through the by-pass pipe 18. Then the valves 20 are closed, the valves 19 are opened, and a faucet is opened, whereupon the water from the main advances the ice toward the said open faucet.

Carbonic acid gas discharged from the tank 1 under high pressure will quickly cause vapor or moisture to freeze and thus effectually close the valve 3 and small discharge pipe 5. To avoid this freezing, suitable means is preferably employed for directing heat against said valve 3. While any preferred means may be resorted to, that shown in the drawings has been found

efficient for the purpose, the same consisting of a small boiler 21 having a steam-pipe 22 leading therefrom through the cylinder 2 and adapted to discharge steam against said valve 3. A throttle valve 23, a steam-gage 24, and a pop safety valve 25 are preferably provided in said steam-pipe, as shown. Water is supplied to the boiler in any appropriate manner, as by a pipe 26 connected to the pipe 8, a valve 27 being provided in said pipe 26.

The cylinder 2 serves to confine the steam discharged from steam-pipe 22, which steam is utilized for heating the tank, causing the inclosed gas to expand and, consequently, increasing the pressure.

Adjustable oppositely disposed clamps are employed for supporting the tank 1 within the cylinder 2, said clamps comprising curved supporting plates 28 having stems 29 fixed thereto and projected outward through the cylinder wall.

Having thus described my invention, what I claim as new, and desire to secure by Letters Patent, is—

1. Apparatus for flushing house-service water pipes, comprising a tank containing gas under high pressure, a pipe leading from said tank and adapted to be connected to a service pipe, a valve-closed drain pipe connected to the first mentioned pipe, means for introducing an abrading material in the service pipe, means whereby water is permitted to pass around the abrading material in one direction, and means whereby the last mentioned means is closed.

2. Apparatus for flushing house-service water pipes, comprising a tank containing gas under high pressure, means for connecting said tank to a service pipe, means for introducing an abrading material in the service pipe, a by-pass pipe through which water is permitted to pass around the abrading material in one direction, and means whereby the water may be caused to act upon said material for forcing the latter in the opposite direction.

3. Apparatus for flushing house-service water pipes, comprising a high-pressure gas tank, means for connecting said tank to a service-pipe, means for directing gas from said tank into said pipe to produce a violent impact with the water in the latter, means for cutting off the gas-supply, and means for allowing the water and extraneous matter dislodged by said impact to escape from said pipe.

4. Apparatus for flushing house-service water pipes, comprising a high-pressure gas tank, means for connecting said tank to a service-pipe, means for directing gas from said tank into said pipe for delivering a violent shock to the column of water in the latter, means for cutting off the gas-supply

to allow the water to rush back through said pipe, means for introducing an abrading material into said pipe, means associated with the last mentioned means whereby, 5 when the gas pressure in the pipe is relieved, the force of the returning water is caused to act upon said abrading material, moving the latter through said pipe, and means for

allowing the returning water and dislodged extraneous matter to escape from said pipe.

In testimony whereof I affix my signature in presence of two subscribing witnesses.

GEORGE W. REDEKER.
